AIR CIRCULATING SYSTEM FOR REFRIGERATOR CARS AND THE LIKE

William E. Van Dorn, Pasadena, Calif., assignor, by mesne assignments, to Pacific Railway Equipment Company, Los Angeles, Calif., a corporation of California

Application January 3, 1938, Serial No. 183,235

8 Claims. (Cl. 98—6)

This invention has to do with air circulating and ventilating systems and apparatus, and, in its more particular aspects, with such systems and apparatus for refrigerator cars. Although the apparatus invention hereinafter described may be useful for purposes other than in refrigerator cars or other refrigerator compartments, the invention has as its primary purpose the circulation of air in such cars or similar compartments and accordingly will be described with that purpose in view.

The general objects of the present invention are to provide a positively driven air circulating system that is of low cost, easy and simple of installation, requires minimum servicing, does not interfere with the normal loading space or structure or operation of a car; and that is capable of maintaining a high efficiency of operation when driven from the car wheels or axles, regardless of the circumstances of loading or operation of the car. It is not necessary that the devices of the present invention be so driven, and they may be driven by independent power; but it is an object of the invention to provide a system that will attain and maintain high efficiency under all circumstances of driving and car operation and loading.

In satisfying these objects and requirements, this invention provides location of circulating fans in the space beneath the lading floor or floor rack, and between that floor rack and the main floor of the car. That space, constituting an air duct, is normally approximately 6" high, to the upper surface of the lading floor, and normally extends through the whole width and length of the car between the bunkers.

The novel fan system which I have devised to occupy that space, comprises a plurality of fans, here shown as of the axial flow type, mounted on one or more driving shafts which shafts are mounted transversely of the car. That transverse shaft mounting may be in a direction directly across, at right angles to, the longitudinal axis of the car, or in a direction diagonally across the car or diagonal to the longitudinal axis.

In order to gain efficiency and uniformity of air flow over the entire width of the car, the several fans are enclosed in substantially longitudinal air ducts which direct the air flow longitudinally of the car.

Preferably, a set of such fans, together with the vanes and other structure forming the necessary mountings and the air ducts, are formed as a structural unit, so as to be readily installed and readily removed for repair, servicing or replace-

ment. And these units, as will be hereinafter described are so associated with the car floor and the lading floor as to be readily placeable and removable.

Preferably, for reasons which will become apparent in the following description, the fan unit or units (of which there may be one or more, as hereinafter described) are placed near the end or ends of the loading compartment of the car and near the openings into the ice bunkers. And arrangements are made so that preferably the unit or units at any one end of the car have a common drive means or drive system. As noted before, this drive system contemplates preferably a drive from a car axle; and the following detailed description will include a description of the essentials of such a drive. However, the driving means here described is not per se made the subject-matter of claims of this application, but will be made the subject-matter of a separate application.

For the purpose of describing the present preferred design and operation of a typical form of the invention, and for indicating typical and illustrative variations and modified forms and arrangements, I refer to the accompany drawings in which:

Fig. 1 is a fragmentary longitudinal section taken as indicated on line 1—1 of Fig. 5, showing a typical refrigerator car equipped with one form of my invention, this view showing also the drive system herein referred to;

Fig. 2 is a plan section of the drive system taken as indicated on line 2—2 of Fig. 1;

Fig. 3 is an enlarged sectional elevation taken as indicated by line 3—3 on Fig. 1;

Fig. 4 is a fragmentary plan section of the parts shown in Fig. 1, said section being taken immediately above the lading floor;

Fig. 5 is a similar plan section taken as indicated by line 5—5 on Fig. 1;

Fig. 6 is a detailed enlarged vertical section taken as indicated by line 6—6 on Fig. 5;

Fig. 7 is a sectional plan of the parts shown in Fig. 6;

Fig. 8 is a diagrammatic plan showing another typical arrangement of the fan and shaft unit;

Fig. 9 is a similar diagrammatic view showing another typical arrangement; and

Fig. 10 is a diagrammatic sectional elevation indicating suitable arrangements of the fan units in the end portions of the car and indicating the directions of air flow which may be set up.

I may remark preliminarily that in these draw-

ings, and in the following description, there is no reference made to the admission or entrance of exterior air to the car. Communication of the car atmosphere with exterior air may be in 5 any of the usual manners, when and as desired, or in any other manner. My invention has only to do with the interior circulation of the car atmosphere.

I will first describe the fan and drive arrangement shown in Figs. 1 to 7. In these figures the car floor is shown at 20, the lading floor or rack is designated generally by the numeral 21, the ice compartment generally by the numeral 22, and the bulk-head which separates the ice compartment from the remainder of the car interior is designated by the numeral 23. A typical car under-frame is shown at 24', comprising two longitudinal beams 24 as shown in Fig. 3; a truck is shown diagrammatically at 25 and the wheel 20 axles at 26.

In these particular figures the ventilating fan system, located at one end of the car under the floor rack 21, is shown as a double unit, made up of the two units designated generally in Fig. 5 by the numerals 30 and 31. These two units 25 30 and 31 are identic in structure, excepting only that they form symmetric counterparts of each other with reference to the longitudinal axis of the car; so a detailed description of one of 30 the units will suffice. For this purpose I now make most particular reference to Figs. 5, 6 and 7.

In those figures the unit will be seen to be made up of a base plate 32, preferably of sheet metal with pressed raised ribs 33 along its longitudinal edges. On this base plate, and preferably welded thereto along their lower edges there stands a series of equally spaced vanes 34, which, in general, extend in a direction longitudinal of the car, while the longitudinal extent of base 40 plate 32 is here shown as at 45° to that longitudinal axis. The vanes 34 thus extend diagonally across base plate 32. The vertical end edges of these vanes 34 lie directly on top of the ridges 33a of the ribs 33, and at their lower 45 corners the vanes may have bent out tabs 35 which, welded to the ridges of the base plate, materially increase the strength of the weld and the rigidity of the whole structure.

Two angle forms 37, which may also preferably 50 be of sheet metal, extend longitudinally (of the base plate) at the upper outer corners of the vertical vanes 34. The location of these members 37 is best shown in Fig. 6; they also show in Fig. 4. Mounted on top the vanes 34, and the angle 55 members 37, is a cover plate 38 which preferably has turned down or flanged edges 39 which overhang the vertical flanges of the angle members 37; and bolts 39a or any other suitable securing means may be used for securing the cover plate 60 in place. The overhanging flanges 39 prevent drippage from above passing down directly into the interior of the unit; and the horizontal flanges of the angle members 37 afford supporting surfaces for the contiguous ends of the boards 65 21a of the lading rack; the dimensions of the parts being such that the upper surface of cover plate 38 is flush with the upper surfaces of the lading rack.

Fan shaft 40 is suitably mounted in bearings 70 41 in a position centrally longitudinal of base 32, and preferably equi-distant from base 32 and cover plate 38. On this shaft there is mounted a plurality of fans 42, in such position and so spaced that there is one such fan located in 75 each of the spaces or ducts between adjacent

vanes 34. The relationship of the fans to the adjacent vanes is best shown in Figs. 5 and 7. In these figures it will be seen that the vanes 34, instead of being exactly straight and plane are bent at the points indicated at 43 adjacent the 5 fan peripheries; and the fans are located in circular openings 44 in plates 45 which extend diagonally across the ducts between vanes 34 square to shaft 40 and in the plane of rotation of the corresponding fan. These plates 45 are riveted 10 or welded at 45a to vanes 34 and are similarly secured to base plate 32. The shaft 40 passes through openings 34b in vanes 34. The fan blades of all the fans are so arranged that they all move the air in one relative direction. For 15 instance on rotation in the direction indicated by the arrows in Figs. 1, 5 and 6 they move the air through the ducts in the directions indicated by the arrows in Figs. 5 and 7, that is, longitudinally of the car and to the right in those 20 figures. When the fans rotate in the opposite direction, when the car reverses its direction of travel, the air circulation is toward the left in Figs. 5 and 7. The fan blades are flat, to obtain equal efficiencies in the opposite directions. 25

The bends at 43 in vanes 34 effectually increase the fan efficiency. It will be noted that the bends are so located and shaped that the bent vane surfaces are substantially at right angles to the central plane of rotation of the fan. 30

As stated before, the structure of the unit 31 is the same as that of unit 30, except that it is a counterpart symmetric with relation to the central axis of the car. The same numerals are therefore applied to unit 31. These two units, 35 which go to make up the complete or double unit, are formed at their meeting ends as is best shown in Fig. 5. The base and cover plates of the two units 30 and 31 meet and abut each other along the axial plane 50, which is diagonal to the longitudinal axes of the units themselves. At that end of each unit an up-standing wall 51 is provided, angled in a horizontal plane as shown in Fig. 5, and the shafts 40 extend through these walls. The object of the walls 51 is to prevent influx of outside air, or in general, 40 heat leakage, through the belt opening in the car floor. Inside the chamber enclosed by these walls (the chamber is covered by the two cover plates 38) are located two drive pulleys 52, one on each 50 shaft 40. For purposes of utilizing a common drive for both the units 30 and 31, or for the whole of the double unit thus made up, the two shafts 40 may be interconnected or intergeared in any desired manner; but I prefer to intergear 55 them via separate drives from a common drive mechanism which I will now describe. For this purpose reference is had particularly to Figs. 1, 2 and 3.

The car axle 26 which is most nearly directly 60 below drive pulleys 52 is provided with a split driving drum 60, the drum being of considerable length so as to effectively engage the traction wheels 62, about to be described, in any position which the drum 60 may take as the 65 truck 25 swings about its central vertical axis. Traction wheels 62, for the same purpose of effectively engaging driving drum 60 in any position, are equipped with rubber faces 61. Two traction wheels 62 are illustrated, each provided with a pulley 63 for a purpose which later will be described. The traction wheels 62 are rigidly mounted on shaft 64 carried in bearings 65 which are mounted on the exterior faces of a casing 66 which encloses the grooved drive 70 75

pulley 67 that is also fixedly mounted on shaft 64. Casing 66 is swingingly mounted at its upper end on a transverse pivot bolt 70 which is carried by the lower and forward ends of bracket members 71, which are medially mounted on a cross pivot 69 mounted between the webs of under-frame beams 24. (For convenience in describing this part of the mechanism the left hand end of Fig. 1 will be considered as forward.)

These bracket members 71, are in effect, levers whose adjustment about the cross pivot 69 will raise and lower the casing 66, and the parts carried thereby, to put the traction wheels 62 in proper position with relation to driving drum 60, and to adjust tension on the belts to be herein-after described. The rear upper end of these bracket members 71 is mounted at 72 on the upper end of an adjusting stud 73 between two adjusting nuts 80. The stud 73 is mounted at its lower end at 74 on the cross bracket 75 mounted between flanges 24a of under-frame beams 24.

A spring pressed plunger 85 is pivotally connected at 86 with housing 66 at the side away from wheel axle 26 and a compression spring 87 which is contained within the hollow plunger 85 and in a cylinder 88 in which the plunger telescopes, presses against the end of the plunger and thus constantly presses the traction wheels 62 into proper tractive engagement with driving drum 60. Cylinder 88 is pivotally mounted at 91 on a cross pivot 92 mounted between the webs of the under-frame beams 24.

On the same cross pivot 69 which carries the members 71 there is mounted a pair of arms 95 which extend forwardly from cross pivot 69 and carry at their forward ends a shaft 96 upon which an idler pulley is rotatably mounted. This idler pulley is made up of a central pulley sheave 97 and two outside and preferably larger pulley sheaves 98. A plurality of belts 99, preferably of V-formation and here shown as three in number, run between the driving pulley 67 and sheave 97; and two sets of V-belts 100, each set here shown embodying two such belts, run from sheaves 98 directly up through the car floor 20 to the pulleys 52 on the fan shafts 40. The driving mechanism is so located on the car frame that the sheaves 98 are as nearly as practicable directly under the pulleys 52, so that the necessarily twisted belt drive between 97 and 52 may be effected without loss of efficiency and without undue wear on the belts.

From the structural description thus far given it will now be readily understood that the idler pulley made up of the sheaves 97 and 98 rides freely on the pivoted arms 95, so that adjustment of the bracket arm 71 about the pivot 69 will be effective to put both sets of belts 99 and 100 under the desired tension. Where the belts 100 run through the car floor, an opening 101 through the floor suffices to pass them, said opening being closed off from the interior of the car by adjoining walls 51 and cover plates 38. In front of the sheaves 97, 98 a guard plate 105 is mounted across the space between under-frame beams 24; and a similar guard plate 106 is mounted between the beams behind the drive mechanism in such a position as shown in Fig. 1. Also other guard plates 107 are mounted in horizontal position across and between the beams 24, in the positions best shown in Figs. 1 and 3. These guard plates not only protect the mechanism from flying debris but also prevent unauthorized access to the vulnerable parts of the

drive mechanism to prevent its mal-adjustment or damage by any unauthorized person.

At times when the car stands idle, it may be desired to maintain the forced air circulation within the car. For this purpose, the above mentioned pulleys 63 are provided which may be drivingly connected with some auxiliary motive source (not shown). Wheels 62 then are held out of engagement with drum 60 by the insertion of a pin (not shown) into manually alined apertures 102 and 103 provided respectively in lug 90 on cylinder 88 and in rod 89 attached to plunger 85.

I have now so far described the structure of one complete unit air circulating unit, including its single drive mechanism. It will be understood that the complete unit which I have now described may be mounted at either end of the car; or that there may be two such complete units, mounted one at each end of the car. In the latter case it will be most convenient to provide for the second complete unit another drive mechanism such as has been described, so as to drive that complete unit also from the car axle most nearly directly underneath.

The individual units 30 and 31 of the preferred unitary arrangement which I here describe, are preferably physically separate from each other and are independently mounted on the car floor. To mount and hold them in fixed position on the car floor it is of course preferred to fasten them down to the car floor by some suitable means, such as by screws or bolts. But whatever the means, it is preferably a means that is easily releasable, so that the units may be easily removed from the car for servicing, repair or replacement. And it may be remarked that the described engagement of the lading floor with the units assists materially in holding them in place.

I have described how the boards or slats 21a of the lading floor or rack have their ends resting on the ledges provided by the angle members 37. It is usual, in refrigerator cars, to provide these floor racks in at least two sections, divided down the middle of the car. Thus in Fig. 4 a section A and a section B are indicated. These sections are usually hinged at their outside edges to the car structure, and section A shown so hinged at 110. As shown in Fig. 4 the end portions 21a of certain of the slats of sections A and B are cut off diagonally so as to fit upon the diagonally extending shelf provided by the angle members 37. The section C of the lading floor or rack which lies between the two units 30 and 31 is framed into a single section with its slats 21 having ends 21a cut off diagonally as illustrated, also to rest on the angle members 37; and this whole section C is hinged at its end at 111.

To get at the fan units it is only necessary to swing the floor racks up and to remove the cover plates 38. To remove the units for servicing, repair or replacement, it is only necessary to lift the floor racks, loosen the driving belts and release whatever securing means is used to hold the unit to the car floor. The unitary construction, and ease with which the units can be removed from the car, are one practical feature of my invention. That feature makes it possible to remove units that are worn or need servicing, and replace them with perfect units, in much less time than would ordinarily be required to service the mechanism in place or to repair it in place.

I refer now to Figs. 8 and 9 which show typical and illustrative variations of shafting and fan

arrangements. For instance, in Fig. 8, a single drive shaft 40c is shown extending diagonally across substantially the complete width of the car. The longitudinal guide vanes 34c are indicated. The single shaft 40c carries the plurality of spaced fans 42c, and a single drive pulley 52c is shown at the center of the shaft. The arrangement here typified may be mounted in the space below the lading rack, as before described.

10 In Fig. 9 I show again a single shaft 40d with a drive pulley 52d at its center, but the shaft in this case extends at right angles directly across the car. The vanes 34d in this case are shown as having offset bends 34e; and the fans 42d are 15 mounted between the offset bend portions of the vanes. Upon operation, the fans in this layout will tend to drive the air longitudinally of the shaft 40d; but the bends in the vanes cause the air to take such a path as is indicated by the 20 arrows in the figure.

From what I have said it will be seen that the sets of fans may be located at either one end or both ends of the car, mounted upon either a single shaft or a plurality of shafts; that the shaft 25 or shafts may extend directly across the car or at an angle across it, and that the vanes in any case will be arranged so as to direct the air longitudinally of the car and uniformly over its entire width, being bent or straight as the circumstances may require.

The direction of circulation, and the number of fan sets (whether at one end only or at both ends of the car) may be as desired to provide the most uniform and maximum air flow. In 30 Fig. 10 I have shown in diagram the lading rack 21, the car floor 20, the ice compartment bulkheads 23, the ice compartments 22; and I have indicated at F and F₁ a fan which may be taken to typify the fan sets or units which I have 35 described. I may assume first that a fan set or unit is only used in the position indicated at F, there being none at F₁. In that case rotation of the fan will circulate the air around in a major circuit uniformly throughout the length and 40 width of the car, under the lading rack 21, up through one ice compartment 22, along the length of the car to the top of the other ice compartment, and down through it. The major circulation is 45 shown by the full line arrows; and the direction 50 of that circulation around through the car will depend on the direction of operation of the fan unit F, depending on the direction of car movement. Either direction of circulation I find to be satisfactory.

55 It will of course be understood that there is minor circulation of the air through the car load, regardless of what type of major circulation is set up; but it is here not necessary to speak in detail of the minor circulation.

60 Utilizing also a fan unit or set at F₁, the same type of single circuit circulation as above described may be utilized, providing only that the direction of operation of fan set F₁ is the same as that of fan set F. However, if fan set F₁ be 65 driven in such a direction as to circulate the air relatively oppositely, then a double circuit circulation is set up whose major paths are shown by the dotted line arrows, the direction of circulation in each of these paths depending upon the 70 direction of operation of the two fan sets and the direction of car travel. It is thus within the scope of my invention to so arrange, and to so drive the fan sets, that circulation or circulations of any desired form and direction may be set up.

75 And it will be further understood that, in giv-

ing the foregoing specific and definite descriptions, I have done so only for the purpose of fully and clearly describing preferred forms and designs of my invention in order that the invention may be understood through the medium 5 of a clear understanding of illustrative forms. The foregoing descriptions are not intended as limitations upon the invention itself, which I do not wish to be considered as limited, except as specifically so stated in the following claims. 10

I claim:

1. In a refrigerator car having a floor and a lading floor spaced thereabove, the combination of two fan shafts located in the inter-floor space, extending diagonally transversely of the car in 15 V-formation symmetric relative to the central longitudinal car axis and with ends in proximity, fans spacedly mounted along both shafts, air directing vanes associated with the fans and adapted to direct air flow in a direction substantially longitudinally of the car, and a common means for driving both shafts. 20

2. In a refrigerator car having a floor and a lading floor spaced thereabove, the combination of a fan unit located in the inter-floor space, 25 said unit including an elongate base plate located on the car floor and extending transversely of the car, a plurality of air deflecting vanes mounted on the base plate, spaced along its length, and forming between them air ducts 30 adapted to direct air flow in a direction substantially longitudinal of the car, a fan shaft extending longitudinally of the base plate, a plurality of fans driven by said shaft and located in the several air ducts, structure associated with the air 35 deflecting vanes and forming supported ledges adapted to support the lading floor, and a cover plate mounted upon the air deflecting vanes and having an upper surface flush with the lading floor; and means to drive said fan shaft. 40

3. In a refrigerator car having a floor and a lading floor spaced thereabove to define a horizontally extending air flow passage, the combination of a fan shaft extending transversely of the car in the horizontal air flow passage between the two floors, a plurality of air moving fans mounted spacedly along the shaft, driven thereby, and located substantially exclusively in the space between the two floors, air flow directing members associated with the fans, located substantially exclusively in the air flow passage between the two floors, and acting to direct air flow in a direction substantially longitudinally of the car, and means for driving the fan shaft. 45

4. In a refrigerator car having a floor, a transverse partition forming one wall of a refrigerating compartment, a lading floor extending from the transverse wall spacedly over the car floor and defining with the car floor a horizontally extending air flow passage, the transverse 60 wall having an opening therein which affords communication for air circulation between the refrigerating compartment and the space between the two floors; the combination of a fan shaft extending transversely of the car in the air 65 flow passage, between the two floors exterior of the refrigerating compartment, a plurality of air moving fans mounted spacedly along the shaft, driven thereby, and located substantially exclusively in the air flow passage between the two floors, and acting 70 to direct air flow in a direction substantially longitudinally of the car. 75

gitudinally of the car, and means for driving the fan shaft.

the rail shaft.

5. In a refrigerator car having a floor and a lading floor spaced thereabove to define a horizontally extending air flow passage; the combination of an air moving and directing unit comprising an elongate casing extending transversely over the car floor and disposed in the air flow passage between the two floors, said casing including a cover disposed substantially at the level of the lading floor, and said casing having openings at its opposite longitudinal sides so that the casing interior forms a continuation of the air flow passage between the two floors, and means within the casing for moving air therethrough from one side to and out of the opposite side.

6. In a refrigerator car having a floor and a lading floor spaced thereabove to define a horizontally extending air flow passage; the combination of an air moving and directing unit comprising an elongate casing extending transversely over the car floor and disposed in the air flow passage between the two floors, said casing provided with means forming a support for the lading floor, and said casing having openings at its opposite longitudinal sides so that the casing interior forms a continuation of the air flow passage between the two floors, and means within the casing for moving air therethrough from one side to and out of the opposite side.

35 7. In a refrigerator car having a floor and a lading floor spaced thereabove to define a horizontally extending air flow passage; the combination of an air moving and directing unit comprising an elongate casing extending trans-

versely over the car floor and disposed in the air flow passage between the two floors, said casing including a removable cover disposed at the level of the upper surface of the lading floor and adapted to form a load taking part of that floor, and said casing having openings at its opposite longitudinal sides so that the casing interior forms a continuation of air flow passage between the two floors, and means within the casing for moving air therethrough from one side to and out of the opposite side. 5 10

8. In a refrigerator car having a floor and a lading floor spaced thereabove to define a horizontally extending air flow passage; the combination of an air moving and directing unit comprising an elongate casing extending transversely over the car floor and disposed in the air flow passage between the two floors, said casing including a cover disposed substantially at the level of the lading floor, and said casing having openings at its opposite longitudinal sides so that the casing interior forms a continuation of the air flow passage between the two floors, and means within the casing for moving air therethrough from one side to and out of the opposite side, said air moving means including a fan shaft mounted in the casing and extending longitudinally thereof and transversely of the car, a plurality of air moving fans mounted spacedly along said shaft and driven thereby, and air flow directing members in the casing and associated with said fans and acting to direct air flow from one side of the casing to the other.

WILLIAM E. VAN DORN. 35
